(57) **CLAIM**

The ornamental design for the beverage container lid, as shown and described.

DESCRIPTION

FIG. 1 is a front perspective view of the beverage container lid embodying my design;

FIG. 2 is a front elevational view of the beverage container lid;

FIG. 3 is a top plan view of the beverage container lid;

FIG. 4 is a right side elevational view of the beverage container lid, the left side elevational view being a mirror image thereof;

FIG. 5 is a back elevational view of the beverage container lid;

FIG. 6 is a bottom view of the beverage container lid;

FIG. 7 is a longitudinal sectional view taken along line 7-7 of FIG. 2;

FIG. 8 is a referential sectional view showing open condition of the FIG. 7; and,

FIG. 9 is a perspective view of the open lid shown in FIG. 8, showing usage state of the beverage container lid.

The broken lines represent the environment in which the article resides and form no part of the claim.
